ABSTRACT

The combination of a track having a center line and a track section for retarding the acceleration of a railroad vehicle which is rolling at an initial velocity on the track is disclosed. The track section has a first curved wiggle section connected to the track as a continuation of the track. The first curved wiggle section bends away from one side of the center line of the track and then bends back to the center line of the track. A reverse curved wiggle section is connected to the first curved wiggle section as a continuation of the first curved wiggle section. The reverse curved wiggle section bends away from the other side of the center line of the track and then bends back to the center line of the track, so that:

1. the pressure of the flanges of the wheels of the vehicle on the rails of the track section;
2. the skewing of the trucks of the vehicle; and
3. the varying of the location of the pressure of the bearings of the vehicle on the axle of the vehicle;

retard the acceleration of the vehicle while the vehicle moves through the track section.

WIGGLE TRACK SECTION

BACKGROUND OF THE INVENTION

Heretofore, in many railroad yards, the tracks down which cars are allowed to roll by themselves when being sorted (classification tracks) have a grade (incline) which was originally designed to keep cars rolling without speeding up or slowing down.

The design of railroad cars has improved over the years, so that they roll more easily. A newer car would start to accelerate down a grade which would not cause a car designed 15 or more years ago to speed up. Thus, the problem is that in many older classification yards, cars are speeding up and coupling to other cars at too high a speed, causing damage to cars and loads (lading).

Due to these problems with car and lading damage, it has become necessary to prevent acceleration of cars on hump yard tracks after leaving the final retarder. This acceleration was causing unacceptably high coupling speeds with cars already standing on the track. The hump yard body tracks have, for example, grades of about 0.20 percent (i.e., about 0.2 feet change in elevation for 100 longitudinal feet of track). With many newer cars and some older cars with lubrication pads, these grades have caused acceleration. Even if the cars leave the last retarder at very low speed, an easy-rolling car could be going over 10 m.p.h. by the time it coupled to a car at the far end of the track. For example, with a car having a total rolling resistance of 16 lbs. per ton (an easy-rolling roller-bearing car) on a 0.20 percent grade, an acceleration of 0.039 feet per second per second can be expected. At this acceleration the speed would increase from about 4 m.p.h., (the recommended maximum coupling speed at which the car leaves the last retarder) to about 10.3 m.p.h. 2,500 feet further down the track. With a tail wind the acceleration could be greater. These facts do not indicate an original deficiency in the design of a yard which may have been built around 1950. It is basically that cars have changed and have been made to roll easier by roller bearings and lubrication pads and also by better center plate lubrication thereby causing less binding of the trucks on curves. Data obtained over the years has shown this improvement in rollability.

Another factor is the length of classification tracks in the hump yard. Because they also serve as departure tracks, they are quite long and this increases the velocity which cars can achieve accelerating down a grade.

A standard solution to the acceleration problem would be to change the grade of the body tracks to a figure of about 0.08 percent (i.e., about 0.08 foot change in elevation for 100 longitudinal feet of track). This would be an expensive procedure costing about \$2,000,000, since some of the tracks are over 4,000 feet long, and would involve raising the level of the tracks about five feet. Inert retarders placed at intervals on each track would also help, but with, for example, about 57 tracks in a hump yard this would involve considerable expense and maintenance problems. Several years previous, weigh-responsive retarders were tried with no satisfactory effect.

We are aware of the following prior art:

U.S. Patent No.	Inventor	Issued	Class
11,650	MORSS	9/5/54	—
1,749,803	DEACON	3/11/30	—
1,776,107	DEACON	9/16/30	—
1,776,108	DEACON	9/16/30	—

OBJECTS OF THE INVENTION

It is the general object of this invention to avoid and overcome the foregoing and other difficulties of and objections to prior art practices by the provision of an improved track section in combination with a track which:

- a. makes unnecessary extensive grading and disruption of tracks which would be needed to achieve the same reduction in acceleration by changing the grade of the tracks;
- b. prevents excess acceleration, reduces damage caused by impacts of one car with another at too high a velocity, thus preventing damage to cars and lading;
- c. is easily and inexpensively installed by existing machinery now normally used for keeping tracks straight and smooth for high-speed operation;
- d. can be modified without requiring new material if more or less retardation is needed in future, because (except for the kinked rail embodiment) the rail is not permanently bent; and
- e. can usually be installed on existing tracks without requiring any change in adjacent tracks.

BRIEF SUMMARY OF THE INVENTION

The aforesaid objects of this invention, and other objects which will become apparent as the description proceeds, are achieved by providing the combination of a track having a center line and a track section for retarding the acceleration of a railroad vehicle which is rolling at an initial velocity on the track. The track section has a first curved wiggle section connected to the track as a continuation of the track. The first curved wiggle section bends away from one side of the center line of the track and then bends back to the center line of the track. A reverse curved wiggle section is connected to the first curved wiggle section as a continuation of the first curved wiggle section. The reverse curved wiggle section bends away from the other side of the center line of the track and then bends back to the center line of the track, so that:

1. the pressure of the flanges of the wheels of the vehicle on the rails of the track section;
2. the skewing of the trucks of the vehicle; and
3. the varying of the location of the pressure of the bearings of the vehicle on the axle of the vehicle;

retard the acceleration of the vehicle while the vehicle moves through the track section.

BRIEF DESCRIPTION OF THE SEVERAL VIEWS OF THE DRAWINGS

For a better understanding of this invention, reference should be made to the accompanying drawings, wherein like numerals of reference indicate similar parts through the several views and wherein:

FIG. 1 is a plan view of a portion of a railroad classification yard showing the hump, the switches for con-

ducting a rolling car from the main track along auxiliary tracks and through additional switches to a body track containing the improved track section of the present invention;

FIG. 2 is a diagrammatic side elevational view of FIG. 1 showing the main track, the hump and the auxiliary tracks leading to the particular body track containing the track section of the present invention;

FIG. 3 is an enlarged diagrammatic plan view of a one embodiment of an improved track section taken along the lines 3-3 of FIG. 1 in the direction of the arrows; and having a total length of about 250 feet and about a 3° curve, and a length of about 50 feet and a deflection of about 2 inches in each first curved wiggle section and in each reverse curved wiggle section.

FIG. 4 is an enlarged diagrammatic plan view of the first curved wiggle section shown in FIG. 3;

FIG. 5 is a view similar to FIG. 4 of another embodiment of the improved track section having about a 6° curve, wherein each first curved wiggle section and reverse wiggle section has a length of about 36.2 inches and a deflection of about 2 inches;

FIG. 6 is a view similar to FIG. 5 of another embodiment of the improved track section having about a 12° curve wherein each first curved wiggle section and reverse wiggle section has a length of about 25 feet and a deflection of about 2 inches;

FIG. 7 is a view similar to FIG. 6 of another alternative embodiment of the track section showing a plurality of kinks connected by straight rail sections in the first curved wiggle section and reverse curved wiggle section, the improved track section having an equivalent curvature of about 26° and a deflection of about 2 inches;

FIG. 8 is a diagrammatic plan view showing a straight track, a straight track wiggle section and a straight other track as a continuation of a straight track section;

FIG. 9 is a view similar to FIG. 8 showing straight track, a straight track wiggle section and a curved other track;

FIG. 10 is a view similar to FIG. 9 showing a straight track, a curved track wiggle section and a curved other track;

FIG. 11 is a view similar to FIG. 10 showing a curved track, a curved track wiggle section and a curved other track;

FIG. 12 is a diagrammatic side elevational view showing a flat track, a flat track wiggle section and a flat other track;

FIG. 13 is a view similar to FIG. 12 showing the track on an upgrade, the track wiggle section on an upgrade and other track on an upgrade;

FIG. 14 is a view similar to FIG. 13 showing the track on a downgrade, the track wiggle section on a upgrade and the other track on a downgrade;

FIG. 15 is a view similar to FIG. 14 showing the track on a curved upgrade, the track wiggle section on a curved downgrade and the other track on a curved upgrade;

FIG. 16 is a view similar to FIG. 15 showing the track on a straight upgrade, the track wiggle section on a straight downgrade and the other track on a straight downgrade; FIG. 17 is a bar graph showing the percent of cars which accelerated on consecutive straight portions of track as compared with the percent of cars which accelerated on about 12° track sections having

a length of about 150 feet; on about 6° curved track sections having a length of about 300 feet; on about 3° track sections having a length of about 300 feet; and on about 26° kinked track sections having length of about 39 feet; and

FIG. 18 is a graph utilizing feet from a starting point (at which the cars are going about 4 m.p.h.) as an abscissa and the velocity of the car in m.p.h. as an ordinate and showing in the solid line curve the acceleration of the cars tested on a conventional track not having the wiggle curve track, and showing in the dotted line curve, what would have happened to the cars if the wiggle curve track section had been installed in such track.

Although the principles of this invention are broadly applicable to railroad track in general this invention is particularly adapted for use in conjunction with a classification yard for sorting and directing railroad cars and hence it has been so illustrated and will be so described.

DETAILED DESCRIPTION

With specific reference to the form of this invention illustrated in the drawings, and referring particularly to FIG. 1, 2, a portion of a railroad classification yard for sorting and directing railroad cars (not shown) is indicated generally by the reference numeral 10.

This railroad classification yard 10 may consist of, for example, a main track 12 (FIGS. 1, 2) which moves up a hump 14 (FIGS. 1, 2) where the individual railroad cars, (not shown) to be sorted and directed are weighed on a scale 15 (FIGS. 1, 2) and are uncoupled from the adjacent car or cars (not shown) so that the uncoupled car (not shown) rolls down the downgrade 16 (FIGS. 1, 2) of the main track 12 through retarders 18 (FIGS. 1, 2) and through a switch S1 (FIGS. 1, 2) on an auxiliary track 20 (FIGS. 1, 2), through another switch S2 (FIGS. 1, 2) onto body track T1 containing the improved track section 30 of the present invention.

These track retarders 18 may be of the type manufactured by General Railway Signal Company, Rochester, N.Y., or may be track skates of the type manufactured by Track Specialties Company, Box 729, Westport, Conn.

These body tracks T1 through T9 are numbered from the bottom to the top of FIG. 1. Each improved track section 30 may, for example, but not by way of limitation, have a total length L_t of about 250 feet (FIGS. 1, 3) and be separated from each other by conventional track sections 31 of the body tracks T1-T9 having a length L_c of about 250 feet (FIG. 1).

TRACK SECTION 30

The invention relates to a track including the tracks 12, 16, 20 (FIGS. 1, 2) and a conventional portion 31 of (for example), the body track T1, having a center line AA (FIG. 3) and the plurality of separated track sections 30 for retarding the acceleration of a rolling rail vehicle V which is rolling at an initial velocity on the main track 12 when such vehicle rolls through the separated track sections 30.

The improved track section 30 has a plurality of first curved wiggle sections 32 (FIG. 3) connected to the conventional portion 31 of the body track T1 as a continuation of such track portion 31. Each first curved wiggle section 32 bends away from one side (in this case the upper side) of the center line AA (FIG. 3) of

the track portion 31, the rails of the track remaining generally parallel, and then bends back to such center line AA of the track portion 31 of the body track T1.

As shown in FIG. 3, the first curved wiggle sections 32 are connected to a reverse curved wiggle section 34 as a continuation of an adjacent first curved wiggle sections 32. Each reversed curved wiggle section 34 (FIG. 3) bends away from the other side (in this case the lower side) of the center line AA of the conventional portion 31 of the body track T1 the rails of the track remaining generally parallel, and then bends back to the center line AA of the conventional portion of the body track T1.

If for example, it is necessary to couple a rolling car (not shown) with a stationary car or slow moving car (not shown) in the improved track section 30, it is essential that the deviation X (FIGS. 3, 4) of the track section 30 be not greater than about 2 inches. Accordingly, the track section 30 shown in FIG. 3 having a total length L_t of about 250 feet is divided, for example, into three first curved wiggle sections 32 connected by two reversed curved wiggle sections 34, each having a length L of about 50 feet, a deflection X of about 2 inches, about a 3° curve and a radius of about 1910.1 feet.

A 3° curve is defined by the angle $y = 3^\circ$ (FIG. 4) formed by the intersection of a tangent, for example, to the starting point A_1 of a first curved wiggle section 32 and another tangent to such first wiggle section 32 at the termination point B_1 where points A_1 and B_1 are about 100 feet apart or the length L of such first curved wiggle section 32 is 100 feet. However, in FIG. 3,

the vehicle V on the rails of the track section 30; the skewing of the trucks (not curved of the vehicle and the varying of the location of the pressure of the bearings (not shown) of the vehicle on the axle (not shown) of the vehicle reduce the acceleration of the vehicle while it moves through the track section 30.

ALTERNATIVE EMBODIMENTS

It will be understood by those skilled in the art that 10 alternatively as shown in FIG. 5, a track section 30⁵ has first curved wiggle sections 32 and reversed wiggle sections 34, each having a length L of about 36.2 feet and a deflection X of about 2 inches, a radius of about 955.4 feet and about a 6° curve.

15 The track section 30⁶ shown in FIG. 6 has about a 12° curve and the first curved wiggle sections 32 and the reverse curved wiggle sections 34 each have a length L of about 25 feet, a deflection X of about 2 inches and a radius of about 478.34 feet.

20 As shown in FIG. 7 a pair of rails 36, each having a length L_t of about 39 feet and the track section 30⁷ having kinked lengths of L_a equal about 6 feet, L_b equal about 10 feet, and end sections L_e equal about 2.5 feet. The rails 36 are kinked at K1, K2, K3, K4, K5, K6 to form the first curved wiggle section 32⁷ and the reverse wiggle section 34⁷. This track section 30⁷ is equivalent to about a 26° curve and has a deflection X of about 2 inches.

25 The results of the tests performed on the embodiments of the track section shown in FIG. 3 through 7 are contained in Table 1, on Page 11. The results of the data shown in Table 1 are illustrated in FIGS. 17 and 18.

TABLE 1

SUMMARY OF DATA*

Track No.	Modifications to 300 Ft. Section	Number of Cars or Cuts Recorded	Average Change in Speed (MPH)	Average Change in Speed Per 100 Ft. of Wiggle	Percent of Cars Accelerating
25	None-Left Straight	157	-0.174	—	25.1%
25	150 Ft. 12° Wiggle	198	-0.920	-0.497	11.8%
26	None-Left Straight	459	+0.224	—	61.9%
26	300 Ft. 6° Wiggle	246	-0.522	-0.249	16.5%
27	None-Left Straight	249	+0.011	—	51.2%
27	300 Ft. 3° Wiggle	385	-0.120	-0.044	44.6%
27	39 Ft. Kinked Rail (26° Equivalent)	255	-0.249	-0.667	33.4%

*Note: All Track Sections 30 Tested were about 300 Ft. Long

where the length L of the sections 32, 34 is 50 feet, the total deflection angle of each such section is 1.5° .

Each reversed curved wiggle section 34 (FIG. 3) is connected to an adjacent first curved wiggle section 32 as a continuation of such first curved wiggle section 32. Each reversed curved wiggle section 34 bends away from the other side (the lower side as shown in FIG. 3) of the center line AA of the conventional track portion 31 of the body track T1 and then bends back to the center line AA of the conventional track portion 31 of the body track T1.

OPERATION

It is believed that when a railroad vehicle V is rolling at a particular velocity on the track section 30, the pressure of the flanges (not shown) of the wheels W of

OTHER ALTERNATIVE EMBODIMENTS

As shown in the plan view of FIG. 8, the track 31⁸ preceding the track section 30⁸ may be straight. The track section 30⁸ may be straight and another track 31a⁸ on the left-hand end of the track section 30⁸ may also be straight.

55 In FIG. 9, the track 31⁹ may be straight; the track section 30⁹ may be straight; and the other track 31a⁹ may be curved:

60 FIG. 10 shows a straight track 31¹⁰, a curved track section 30¹⁰ and a curved other track 31a¹⁰.

In FIG. 11 the track 31¹¹ is curved; the track section 30¹¹ is curved; and the other track 31a¹¹ is also curved.

65 In the side elevational view of FIG. 12 a flat track 31¹², a flat track section 30¹², and a flat other track

$31a^{12}$ are shown separated by points of inflection or separation I_1 .

FIG. 13 shows a track 31^{13} on an upgrade, a track section 30^{13} on an upgrade and another track $31a^{13}$ on an upgrade.

In FIG. 14 the track 31^{14} is on a downgrade; the track section 30^{14} is on an upgrade; and the other track $31a^{14}$ is on a downgrade.

In FIG. 15 the track 31^{15} is curved upwardly on an upgrade; the track section 30^{15} is curved downwardly on a downgrade; and the track $31a^{15}$ is curved upwardly on an upgrade.

FIG. 16 shows a generally straight track 31^{16} on an upgrade; a generally straight track section 30^{16} on a downgrade; and a generally straight other track $31a^{16}$ on a downgrade.

SUMMARY OF THE ACHIEVEMENTS OF THE OBJECTS OF THE INVENTION

It will be recognized by those skilled in the art that the objects of this invention have been achieved by providing an improved track section 30 , FIGS. 1, 2, 3, etc., in combination with a track 31 , which combination makes unnecessary any extensive grading or disruption of existing track which would be needed to achieve the same reduction in the acceleration of rolling cars V by changing the grade of the tracks; which prevents excessive acceleration, reduces damage caused by the impacting of one car with another car at excessive speed thus preventing damage to the cars and lading contained therein; which provides an easy and inexpensive installation by existing conventional rail forming machines normally used for keeping the tracks straight and smooth for high speed operation; which can be modified without the use of new material as more or less retardation needed and can usually be installed on existing tracks without any change in adjacent tracks.

While in accordance with the patent statutes a preferred and alternative embodiments of this invention have been illustrated and described in detail, it is to be particularly understood that the invention is not limited thereto or thereby.

We claim:

1. In combination, with a rolling rail vehicle of the type having wheels for riding on a track and rolling free of the engine, such as in a railroad classification yard, the improvement which comprises:

a first curved wiggle section having generally parallel rails connected to said track as a continuation of said track;

said first curved wiggle section bending away from one side of said center line of said track and then bending back to said center line of said track; a reverse curved wiggle section having generally parallel rails connected to said first curved wiggle section as a continuation of said first curved wiggle section; said reverse curved wiggle section bending away from the other side of said center line of said track and then bending back to said center line of said track; so that the pressure of the flanges of the wheels of said vehicle on the rails of said track section; the skewing of the trucks of said vehicle; and the varying of the location of the pressure of the bearings of said vehicle on the axle of said vehicle; retard the acceleration of said vehicle while said vehicle moves through said wiggle section.

2. The combination recited in claim 1 wherein said track is straight.

3. The combination recited in claim 1 wherein said track is curved.

4. The combination recited in claim 1 and having another track connected to said reverse curved wiggle section.

5. The combination recited in claim 4 wherein said other track is straight.

6. The combination recited in claim 4 wherein said other track is curved.

7. The combination recited in claim 1 wherein said track is on a level grade.

8. The combination recited in claim 1 wherein said track is on an incline.

9. The combination recited in claim 1 wherein said track is on an upgrade.

10. The combination recited in claim 1 wherein said track section is on a level grade.

11. The combination recited in claim 1 wherein said track section is on an incline.

12. The combination recited in claim 4 wherein said other track is on a level grade.

13. The combination recited in claim 4 wherein said other track is on an incline.

14. The combination recited in claim 1 wherein said first curved wiggle section has a plurality of kinks.

15. The combination recited in claim 14 wherein said reverse curved wiggle section has a plurality of kinks.
